TASSEL

Carmen S. Felch, Providence, R. I., assigner to
Ernest E. Weller, Providence, R. I.

Application May 8, 1939; Serial No. 272,327

3 Claims.

(Cl. 2—278)

This invention relates to a tassel of the type more especially for use on articles of wearing apparel, one example being that of the tassel used upon a shoe-lace.

One of the objects of this invention is to provide a tassel of handsome and attractive appearance which may be sufficiently simple to be easily and quickly formed.

Another object of the invention is to provide a tassel, the tuft material of which will be formed of more than one type or color such, for instance, as two colors or two tones of a single color.

Another object of the invention is to provide the tuft material of a tassel in such form that it will lie evenly.

Another object of the invention is to provide the material of the tuft portion so that there may be overlapping of one part with another in such an arrangement that the parts will lie smoothly and evenly without buckling or protruding out from the general body of the tassel.

Another object of the invention is to provide a tassel of hollow formation and of such a character that it will maintain itself in a definite formation with the material so arranged that it will be attractively displayed. Another object of the invention is economy of tuft material by reason of the shaping of the pieces so that minimum waste of material will occur.

With these and other objects in view, the invention consists of certain novel features of construction, as will be more fully described, and particularly pointed out in the appended claims.

In the accompanying drawing:

Fig. 1 is an elevation of the tassel in completed form.

Fig. 2 is a top plan view of the tassel.

Fig. 3 is a central sectional view of the tassel.

Figs. 4 and 5 are perspective views of two parts of the tuft material.

Fig. 6 is a sectional view of a tassel having a modified form of cap for holding the tuft material in position.

A tassel of the general character which is here illustrated is shown in patent to Weller 2,107,459 dated Feb. 8, 1938. This patented tassel has a tuft material of all one piece of fabric. Such a tassel requires a comparatively large portion from which to cut the required star formation and when such single piece of material is bent down into place frequently there occurs a buckling at the cut edges causing the material to protrude outwardly to detract from the appearance of the tassel. In order to overcome these undesirable effects, I have formed a tassel

of a plurality of pieces of material, that illustrated being two pieces which I have disposed in a crossing relation allowing of smaller pieces of material to be utilized, also permitting of overlapping at the edges without a buckling and distorting of the shape of the tassel and I further permit of a tassel being formed of two different colors or two tones of one color whereby a greater variety of tassels may be provided, and the following is a more detailed description of the present embodiment of this invention, illustrating the preferred means by which these advantageous results may be accomplished:

With reference to the drawing: 10 designates 15 one piece of tufted material and 11 another piece of tufted material. This material may be leather or some sheet like substances capable of having the desired formation. These pieces are provided with oppositely extending petal like formations 12 and 13, joined together by a neck portion 14 which is provided with an opening 15. The piece 10 is here shown as of a different color material than the piece 11 so that a contrast in the appearance of the petals of the two pieces 20 may be provided. This contrast may be either different colors, different shades of the same color, or different finishes of one material than the other; for instance, an embossing of the material of one and a plain piece of material on the other will serve to provide this contrasting appearance.

When the tufted material is thus provided it is assembled by placing the piece 10 and the piece 11 at right angles with the opening 15 registering and is then forced into a cap 16.

The cap 16 has a top wall 17 and a neck 18. The top wall 17 is curved downwardly and inwardly as at 19 in the form shown in Figs. 1 and 3, while in the form shown in Fig. 6 the wall is 25 curved downwardly alone as at 20 rather than downwardly and inwardly as above described.

This cap receives the two pieces 10 and 11 when the crossing neck portions 14 of the right angularly disposed pieces are forced into the walls of the cap 16 causing their petal like formations 12 and 13 to be bent downwardly as 30 illustrated in Figs. 1, 3 and 6 to be disposed at a small angle to the axis of the tassel that is less than 22½ degrees or in other words nearly 35 parallel with the central longitudinal axis of the cap; and in order that the tuft material thus formed may be secured in place, I pass a tubular member 21 thru the openings 15 and into the neck 18 of the cap 16 while the flange 22 of this 40 tubular member engages the neck 14 about the 45

opening 15 and forces these neck portions snugly against the under-surface of the top wall 17. A tight friction fit serves to hold the tubular member in engagement with the inner surface of the neck 18 to complete the tassel.

In use, this tassel may be threaded upon a shoe-string or the like extending axially of the tassel and a knot tied in the end of the string to fit up into the hollow formation of the tassel and there be concealed, or this tassel may be applied in various other ways to the ends of string-like members in a known manner.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A tassel comprising a tuft formed of a plurality of elongated pieces of material of a length substantially greater than their width angularly disposed and crossing each other, each with an opening to register with the opening of the companion piece of material, and a cap of cup shape into which the crossing portion of the pieces of material are positioned in generally a U bend of each piece with portions engaging the surrounding side walls of said cap and causing the portions of material protruding from the cap to be disposed downwardly nearly parallel with the central longitudinal axis of the cap.

- 5 2. A tassel comprising a tuft formed of two elongated pieces of material of a length substantially greater than their width angularly disposed and crossing each other at substantially right angles, each with an opening to register with the opening of the companion piece of material, and a cap of cup shape into which the crossing portion of the pieces of material are positioned in generally a U bend of each piece with portions engaging the surrounding side walls of said cap and causing the portions of material protruding from the cap to be disposed downwardly nearly parallel with the central longitudinal axis of the cap.
- 10 15 3. A tassel comprising a tuft formed of two elongated pieces of material of a length substantially greater than twice their width angularly disposed and crossing each other at substantially right angles, each with an opening to register with the opening of the companion piece of material, and a cap of cup shape into which the crossing portions of the pieces of material are positioned in generally a U bend of each piece with portions engaging the surrounding side walls of said cap and causing the portions of material protruding from the cap to be disposed downwardly nearly parallel with the central longitudinal axis of the cap, said cap having an opening registering with the opening in said pieces and a tubular member inserted in said opening and having a flange to bind the pieces between it and said cap.
